United States Patent

Des. 234,494
Patented Mar. 18, 1975

234,494

PACKAGING CONTAINER FOR FOOD OR THE LIKE

Ernst Theodore Theimer, Rumson, and Donald Joseph Roslonski, Bricktown, N.J., assignors to National Electro-Cook Corporation, Brunswick, N.J.

Filed Jan. 4, 1973, Ser. No. 320,876

Term of patent 14 years

Int. Cl. D9—03
U.S. Cl. D9—182

FIG. 1

FIG. 2

FIG. 4

FIG. 3

FIG. 1 is a perspective view of a packaging container for food or the like showing our new design;

FIG. 2 is a top plan view;

FIG. 3 is a front elevational view; and

FIG. 4 is a left side elevational view.

We claim:

The ornamental design for a packaging container for food or the like, substantially as shown.
